DEVICE FOR VENTING OIL BURNER
INSTALLATIONSJames M. Carroll, Philadelphia, Pa., assignor to
Monarch Manufacturing Works, Inc., Philadelphia,
Pa., a corporation of Delaware

Application March 19, 1935, Serial No. 11,774

4 Claims. (Cl. 251—114)

This invention relates to the venting of oil burner installations and includes the structure for venting.

An object of the invention is to provide improved means whereby air accumulation in a device, between oil tanks and burner nozzles, may be easily and quickly vented upon the start of the pump or similar device, the venting to be automatically discontinued upon the replacement of the air by oil.

A further object of the invention is to provide a vent device having improved means for passing air therethrough but to close against the passage of oil.

15 A further object of the invention is to provide a vent device having a valve therein adapted to close to prevent the passage therethrough of oil under pressure and providing means for the passage of air therethrough without the closing 20 of the valve, said air preferably being conducted to the tank from which the oil has been withdrawn so that any oil which may intermingle with the air will be conserved.

The invention therefore is adapted to be used 25 in a system, including a tank, an oil conduit and an air conduit, and comprises a valve structure located in the air conduit adapted to provide for passage therethrough of air but to close against the passage of oil, said vent device comprising 30 a housing which is introduced into the air line and comprising a moving part as a collapsible diaphragm having passages properly proportioned to permit the passage therethrough of air but of such restricted capacity as to obstruct 35 the passage of oil whereby the pressure of the oil will build up pressure in opposition to the collapsible diaphragm and by moving parts of the diaphragm will close entirely to the passage of oil.

40 In the drawings, Figure 1 is a view largely diagrammatic of a conventional oil burner installation, the burner itself being omitted, and including a vent therein.

45 Figure 2 is a similar diagrammatic view with the parts differently arranged.

Figure 3 is a similar diagrammatic view with again a different arrangement of parts.

Figure 4 is a view in side elevation of the vent unit.

50 Figure 5 is a view of the vent unit in substantially diametrical section.

Figure 6 is a view in side elevation of the adjustable valve member.

55 Figure 7 is a view of the adjustable valve mem-

ber in plan as indicated by the arrow 7 at Figure 6 but with parts broken away.

Figure 8 is a view of the flexible diaphragm and guide in side elevation, parts being broken away.

Like characters of reference indicate corresponding parts throughout the several views.

It is well known that in oil burner installations when the pressure discontinues the supply of oil to the burner, the oil will, at least under 10 some conditions, flow reversely into the tank leaving the conduit filled with air. In modern oil burner installations, time switches are provided for discontinuing the motor current if the flame is not established within a predetermined 15 interval after the starting of the pump. When the conduit is of considerable length, the pumping of air through the burner nozzle is a matter of difficulty, especially as the pumps are not particularly adapted for pumping air, and the relief 20 valves ordinarily employed require a predetermined pressure before opening. It often happens, therefore, that the pump fails to void the conduit of air and the time switch, operating, discontinues the current of the motor and the 25 services of a mechanic are required. The present invention is adapted to provide relatively free exit for the air until voided from the conduit sufficiently to permit of pressure being built up in the regulating valve to supply oil to the 30 burner and to automatically close against the passage of any material quantity of oil, whereby the burner is promptly provided with oil in advance of the time limit of the time switch.

As disclosed in the drawings, tank 10, 10' or 35 10'' represent various locations of oil tanks for use with oil burners. A conventional showing of the pump 11 requires the use of conduit 12, 12' or 12'' for conducting the oil from the tank to the pump. In the ordinary installation of oil 40 burners, the valve 13 is employed which receives the oil from the pump through the conduit 14 and after the predetermined pressure has been built up, discharges the oil through the conduit 15 to any type of burner selected. No burner is 45 shown as the burners vary so greatly that any attempt to show the burner has been omitted. This type of pressure valve is well known in the art and after the burner pressure has been exceeded, will by-pass the oil through the loop 16 50 back into the initial conduit.

When the pump 11 discontinues supplying oil to the burner as, for instance, under thermostatic control, the oil may flow backwardly into the tank either to completely void the conduit or 55

partially so. When the pump again starts, it is necessary to educt the air from the conduit before the oil can reach the burner or the control valve 13. As the pumps are arranged for the 5 pumping of oil rather than air and as the valve 13 presents an obstruction to the eduction of the air, the pump frequently fails to overcome the resistance of the valve 13 to discharge the air and the time switch, ordinarily employed in 10 such installations and not shown, functions to break the circuit of the motor. This situation is one which the ordinary user cannot cope with and the services of a mechanic are required. To overcome this drawback, the present invention 15 provides means of easy exit for the air so that although the pump may be intended to function only for oil, the exit of the air is offered with but little resistance and the pump will then very readily and quickly exhaust the air and initiate 20 the pumping of oil.

The device as an entirety is shown at A and may be variously located in the installation at any point between the pump and the tank and bypassing the valve 13. For such purpose, there is 25 shown at Figure 1 a pipe 17 leading from the vent member A to the tank 10, and at Figure 3, the conduit 17' similarly arranged but with the tank differently positioned relative to the pump and the vent A. At Figure 2, the conduit 18 extends 30 as a by-pass from the conduit 14 to the vent A and with the conduit 17'' from the vent A to the tank 10''. Each of these tanks 10, 10' and 10'' are provided with breather devices 19, 19' and 19'', as well known in the art.

35 The vent A comprises the housing 20, having an inlet at 21 and an outlet at 22. The inlet 21 connects with the pipe 23, 23' or 23'' from the pump and the outlet 22 connects directly with the conduits 17, 17' and 17''.

40 The air entering from the pipe 23 into the inlet 21, passes through the lateral passages 24 into the chamber 25 and about and surrounding the flexible diaphragm 26. This flexible diaphragm is provided upon its normally lower end with a 45 guide lug 27 which fits into the passage normally forming communication between the chamber 25 and the inlet 21 and normally closing said passage. The diaphragm is provided with a sleeve 28 forming at its upper end a valve seat. This sleeve 28 50 is provided with constricted passages 29 which form communication between the chamber 25 and the sleeve 28.

55 The flexible diaphragm is provided at its upper end with a flange 30 which is seated upon the annular shoulder 31 within the housing and is maintained fixed in said position by means of the disc 32 which has a threaded perimeter at 34 engaging the threads 35 within the interior of the housing. A multisided boss 36 is provided for 60 the application of a wrench or similar device for the purpose of inserting the disc and forcing it home to clamp the flange 30.

65 This disc 32 is internally screw threaded and the sleeve 37 is threaded into said threads, said 70 sleeve being also internally screw threaded. The flattened part 38 is provided on said sleeve for the application thereto of a wrench or similar implement. By means of the internal threads of the sleeve 37, a needle valve 39 is inserted within 75 the collapsible diaphragm 26 and in position to engage the valve seat of the sleeve 28 when the flexible diaphragm has collapsed. To assist the collapsible diaphragm to resist collapsing, a spring 39' is introduced into the diaphragm chamber and the sleeve 37 is employed to bear upon the upper

end of the spring and by its manipulation to vary the tension of the spring. The needle valve 39 is held in position by the threaded section 40, preferably integral with the needle valve, the kerf 41 being provided for receiving a screw 5 driver, or like implement, to adjust the needle valve relative to the valve seat provided by the sleeve 28. It will be noted, especially from Figure 5, that an annular space 42 is provided within the disc 32, surrounding the sleeve 37. This 10 annular space 42 provides communication from the chamber 25, through the orifices 29, the sleeve 28, and flexible diaphragm 26, to the passages 43 which extend radially from said annular recess to and communicate with the annular furrow 44. 15 This furrow 44 extends entirely about the disc 32 below the threaded part 34. This furrow 44 is in communication with the outlet 22.

In operation, when the pump starts, the air from the pump passes through the by-pass 23 20 and the conduit 17 to the tank 10. The restricted conduits 29 are sufficient to pass the air therethrough by reason of its extreme fluidity. When, however, the air has been completely exhausted and the oil presents itself at the restricted passages 29, the greater viscosity of the oil tends to prevent its passage through these constricted openings 29 and the pressure from the pump, therefore, builds up, and acts upon the flexible diaphragm and closes it against its own resistance 30 and that of the enclosed spring 39' until the sleeve 28 has been lifted so that the needle valve 39 cooperating therewith will close further passage into the chamber 25 and, therefore, close the vent device and the outlet 22. As the vent device 35 is in direct communication with the pressure side of the valve 13, it will be maintained in closed position so long as the pressure continues. When, however, the pressure of the oil is discontinued, the spring 39' will promptly open the passage as 40 described and the vent device is ready for a repeat.

45 Of course, the venting device illustrated may be modified and changed in various ways without departing from the invention herein set forth and hereinafter claimed.

I claim:

1. A vent member for an oil burner installation comprising a housing having a chamber with inlet and outlet ports communicating with the chamber, a collapsible diaphragm mounted within the chamber, a valve seat carried by and movable with the collapsible diaphragm, a valve member adjustably fixed in opposition to the movement of the valve seat, means forming communication between the interior of the collapsible diaphragm and the outlet port, and constricted 50 passages from the chamber through the valve seat tending to provide passage for air by the valve and to resist the passage of oil, the pressure of said oil tending to collapse the diaphragm and move the seat into closing engagement with the valve.

2. A vent member for an oil burner installation comprising a housing having a chamber therein and with an inlet and an outlet port in communication with the chamber, a collapsible diaphragm, a valve seat located within the chamber and carried by the diaphragm, said valve seat being adapted to be closed to interrupt the passage of fluid from the inlet to the outlet 65 port, a valve member cooperating with the said valve seat, means providing for passing air through said valve seat, said means resisting the passage of oil to collapse the diaphragm and close the valve seat.

3. A vent for oil burner installations comprising a housing having a chamber with inlet and outlet ports, a collapsible conduit forming communication between the inlet and outlet ports, a hollow valve seat carried by the collapsible conduit, a valve adjustably fixed for cooperation with the valve seat member, and constricted passages from the chamber to the interior of the valve seat member functioning to pass air through the valve and resist the passage of oil whereby the pressure of the oil is applied for closing the valve.
5. A vent member for oil burner installations

comprising a housing having a chamber therein with an inlet port and an outlet port, a conduit forming communication between said inlet port and outlet port, a movable hollow valve seat associated with the conduit, a valve member adjustably fixed relative to the valve seat, and constricted passages from the chamber to the interior of the valve seat proportioned to pass air by the valve and to resist the passage of oil to move the valve seat into closing engagement with the valve.
